UNITED STATES PATENT OFFICE.

EGBERT B. BROWN, OF MAYWOOD, ILLINOIS.

JOURNAL-LUBRICATOR.

SPECIFICATION forming part of Letters Patent No. 628,921, dated July 18, 1899.

Application filed September 19, 1898. Serial No. 691,393. (No model.)

To all whom it may concern:

Be it known that I, EGBERT B. BROWN, of Maywood, in the county of Cook and State of Illinois, United States of America, have invented certain new and useful Improvements in Journal-Lubricators, of which the following is a specification.

This invention relates to improvements in devices for lubricating railway-car and other journals or journal-bearings and is designed to provide an improved lubricating device entirely detached from the journal bearing or box and designed and adapted for marketing as a complete article of manufacture ready to be inserted in any ordinary car-axle box without requiring any alteration or modification of either the lubricator or the box.

To this end the invention consists in the matters hereinafter set forth, and particularly pointed out in the appended claims, and will be fully understood from the following detailed description of the accompanying drawings, illustrative thereof, and in which—

Figure 1 is a longitudinal section of an ordinary car-axle box, showing a lubricating device constructed in accordance with my invention inserted in operative position therein. Fig. 2 is a transverse sectional elevation taken on line 2 2 of Fig. 1. Fig. 3 is a side elevation of the lubricator with its capillary feeders and lining omitted. Fig. 4 is an end elevation of the frame. Fig. 5 is a top plan view thereof.

In said drawings, J designates the car-axle journal, and J' the box within which said journal has its bearing. As herein shown, this box is of the usual rectangular shape in cross-section, containing in its upper portion the bearing-brass j, against which the journal rotates and above which the usual wedge j' is inserted. The box is shown as recessed at j² at its inner end to contain the usual dust-guard j², and the outer end of the box is provided with a hinged door j⁴, through which access is had to the interior of the box. These features, however, will be understood as involving no part of my invention, being referred to merely for the purpose of rendering the construction clear and being subject to wide variations without in any way affecting the construction or operation of the lubri-

cator, to which this specification particularly relates.

My improved lubricator comprises, essentially, a supporting-framework A, by means of which a hollowing or trough-shaped open-work basket B is resiliently suspended beneath the journal J in such manner that when said basket is lined with a fibrous or capillary material, that also depends through the open basket into the oil in the lower part of the box, the journal will be constantly and perfectly lubricated by the oil which feeds up by capillary attraction to the lining, which will yieldingly be held in contact with the journal. The framework A is of such shape that it can be inserted and removed through the door j⁴ of the box; and to this end it consists in this instance of wire bent so as to provide a horizontal reach a, extending along at each side of the journal parallel thereto and slightly above or adjacent to the level of the axis of the journal. These horizontal reaches are supported at each end by vertical standards a', which are in turn connected at their lower ends by horizontal bars a², that rest upon the bottom of the box. In other words, the shape of the framework is herein shown as such that in end view it presents the shape of an upwardly-open U, the connecting cross-bar a² of which rests on the bottom of the box, while in side view its shape is that of a downwardly-open or inverted U, the connecting portion of which is the horizontal reach a adjacent to the side of the journal. The basket B is supported from the framework thus constructed by a plurality (in this instance four) of tension-springs D, the lower ends of which are hooked into marginal apertures b of the basket and the upper ends of which are hooked over or suspended from the horizontal reaches a of the supporting-frame, depending bends or loops a³ being desirably formed in said reaches at the points of junction with said springs to prevent the latter from becoming displaced thereon at any time, and particularly when the lubricator is tipped up at the angle necessary to its insertion in the box.

The basket B is designedly made sufficiently flexible to insure its readily conforming to the curve of the journal, even though the lat-

ter may vary widely in diameter in the different boxes to which the lubricator may be applied. To this end it may conveniently consist of thin sheet metal or of any other substance suitable for the purpose. As indicated by the term "basket," it is more or less apertured or of open-work and in this instance is shown as provided with a number of longitudinal slots b^2 . The basket is lined 5 with a layer or surface of fibrous or oil-conducting material, as indicated at L in Fig. 2, and from this lining wicks l depend through the apertures b^2 in the basket into the bottom of the box. These wicks will obviously serve 10 to conduct the oil upward to the lining L by their capillary action just as long as any oil remains in the box, and as the basket is drawn yieldingly upward at all times by the springs D, and as the flexibility of the basket results 15 in its conforming perfectly to the lower surface of the journal, the latter will be perfectly lubricated throughout the entire period. In fact, the lubrication resulting so long as any oil remains in the box will be as perfect as 20 though a freshly-oiled pad were held in constant contact with the journal by the hand, the flexible basket with its lining forming a perfect annulus lightly pressed at all times against the lower part of the journal and continuously supplied with oil through the wicking 25 which depends into the oil-chamber beneath. As much oil will be supplied to the box ordinarily as can be contained therein without escaping through the aperture out of 30 which the car-axle passes at the inner end of the box.

In practice the lubricator will be made up complete, with the basket connected to its supporting-framework and with the lining 35 and wicks in position thereon. It may then be inserted in any ordinary journal-box, such as that shown in the drawings, by simply tipping it up at an angle, so as to enable the front lower cross-bar a^2 to be inserted and 40 pushed forward beneath the journal until the lower rear cross-bar is lifted over the lower edge of the door-opening of the box, after which the frame is dropped into its normal horizontal position, as herein shown, the basket 45 in the meantime being forced down against the tension of its springs, so that it will pass also beneath the journal and then allowed to spring back to embrace the lower side of the latter in the manner stated. While thus particularly intended and adapted for insertion 50 in the journal-boxes of railway-cars and like vehicles, it must, however, be understood

that the device is equally applicable to any other form or situation of journal-box to which it may be found adapted. It will also 60 be understood that the device may be widely varied in its details of construction without involving any departure from the broad invention contained therein.

I claim as my invention—

1. A journal-lubricator comprising a supporting-frame, a trough-shaped basket, springs depending from the upper members of the frame and engaging the edges of the basket, a fibrous lining for the basket, and oil-conducting wicks depending from said lining. 65

2. A journal-lubricator comprising a resilient flexible basket disconnected from the bearing, supports arranged on opposite sides of the journal, means resiliently suspending the basket by its said edges from lateral supports, a fibrous lining in said basket, and oil-conducting wicks depending from said lining. 70

3. A journal-lubricator comprising a flexible trough-shaped basket made from sheet metal and disconnected from the bearing, springs engaging the lateral edges of said basket and resiliently suspending it, lateral supports for said springs on opposite sides of the journal, a fibrous lining in said basket 80 and oil-conducting wicks depending from said lining. 85

4. A journal-lubricator comprising a framework removably inserted in the journal-box and having lateral members on opposite sides 90 of the journal, a trough-shaped basket, tension-springs engaging the lateral edges of the basket and resiliently suspending it from said lateral members, a fibrous lining in said basket and oil-conducting wicks depending from 95 said lining.

5. A journal-lubricator comprising a double loop-shaped frame having upper horizontal reaches, lower transverse reaches, and vertical corner-standards connecting said reaches, a trough-shaped metallic basket, tension-springs resiliently suspending said metallic basket by its edges from the upper horizontal reaches of said frame, a fibrous lining or mat in said basket and oil-conducting wicks 100 depending from said lining. 105

In testimony that I claim the foregoing as my invention I affix my signature, in presence of two subscribing witnesses, this 12th day of September, A. D. 1898.

E. B. BROWN.
